Charles McVille Ath. 7/25/33

UNITED STATES PATENT OFFICE

WILLIAM J. KLEMM, OF CHICAGO, ILLINOIS

WINDOW STRUCTURE

Application filed December 31, 1931. Serial No. 584,060.

My invention relates to window structures particularly to window structures of sheet metal and of that type in which the window sashes, in addition to being vertically slideable in the window frame, are adapted to be swung to inclined or ventilating position, or to a horizontal or flat position for washing from the inside of the building.

An important object of the invention is to provide improved means and arrangement for braking and stopping the window sash against vertical movement when the sash is in inclined position.

A further object of the invention is to conceal the brake mechanism and sash supporting parts within channels so that these parts will not be exposed to view and will be protected.

Another object is to provide guide members forming part of the connection between the sash weights and the bottom of the sash for guiding the sash during movement thereof to ventilating or to washing position.

Still another object is to provide improved locking means or latch means for locking the sash against vertical movement when in vertical position.

The above enumerated and other features of the invention are incorporated in the structure shown on the drawings, in which drawings

Figure 1 is a vertical section of the lower part of a window frame, and the lower sash in edge elevation;

Figure 2 is a section through a sash and its supporting channel and mechanism;

Figure 3 is a front elevation of one of the guide channels and supporting mechanism therein;

Figure 4 is an enlarged section on plane 4-4 of Figure 2;

Figure 5 is an enlarged section on plane 5-5 of Figure 3;

Figure 6 is an enlarged section on plane 6-6 of Figure 2;

Figure 7 is an enlarged front elevation of sash lock mechanism; and

Figure 8 is a section like Figure 5 showing the open position of the lock mechanism.

On the structure shown the window frame

comprises a sill 10 and the side or vertical grooves 11 and 12 for the lower and upper sash respectively, the frame being preferably constructed of sheet metal. I have shown the construction and arrangement for control of the lower sash of a window, it being understood in the art that the upper sash may be controlled in the same manner. In each of the side grooves 11 and 12 of the window frame I insert a guide channel 13 preferably of sheet metal and extending from top to bottom of the frame. Each channel has the front flanges 14 and 15 extending inwardly to define a vertical slot 16.

In a manner well known in the art a pulley (not shown) is pivoted on the frame at the upper end of each of its side grooves and around each pulley extends a sash weight cable or tape 17 having its inner end connected to a suitable sash weight (not shown), the outer end of each cable or tape extending downwardly through the corresponding channel 13. In accordance with my invention I provide a flat bar 18 in each of the channels 13 having at its upper end a section deflected inwardly therefrom to provide a hook 19 for receiving a link 20 at the lower end of the sash weight tape 17, the bar at its lower end being secured to a block 21. At its upper end above the hook 19 the bar 18 is secured, as by means of a rivet 22, to a guide frame 23 which may be of U shape cross section to fit within the respective channel 13 for guiding the upper end of the bar 18. The upper end 18' of the bar 18 may be deflected inwardly to form an abutment for the sash tape 17 to hold such tape in vertical alignment within the channel 13. The upper end of the front wall of the frame 23 is depressed to form a seat for the lower end of a pair of brake levers 24 and 25 which extend upwardly and terminate in semi-cylindrical ends 26. Each brake lever has a lateral projection or lug 27 for friction engagement with the sides of the corresponding channel 13 when the brake levers are forced apart, and to obtain sufficient braking surface on the projections they may be continued across the extensions 28 on the backs of the levers.

The window sash may be of conventional

construction comprising the sheet metal rectangular frame 29 having the grooves 30 for receiving the window pane 31. For the purposes of my invention I provide a wall 32 in 5 each side of the sash frame set inwardly a distance from the side edges of the sash frame as clearly shown in Figure 4. A supporting bracket 33 is secured against the front of each inset wall 32 at the lower end thereof 10 and the lower end 33' of the bracket is offset outwardly a distance and has a pivot opening 34 for receiving a pivot stud 35 extending from a guide frame 36 within the adjacent guide channel 13. The frame 36 is of exterior rectangular shape to fit within the guide channel, the front wall of each frame bearing against the corresponding guide bar 18 in the guide channel and the upper ends 37 of the frame extending around the edges of and a 15 distance behind the guide bar to form abutments for engagement with the block 21 secured to the lower end of the guide bar. The pull of the sash weights is communicated through the guide bars 18 and the blocks 21 20 at the lower ends thereof and against the abutments 37 of the guide frames 36.

A distance above the lower edge of each sash frame a pivot fitting 38 is secured against the outer face of the inset wall 32 and 30 to strengthen this wall and the support of the pivot bracket 33 and fitting 38 a metal strip 39 is applied against the inner side of the inset wall 32 and the fittings and the strip secured rigidly together as by means of 35 screws 40.

Each fitting 38 serves to support a pivot pin 41 for pivoting at its lower end an operating arm 42 and these arms may be in the form of flat metal strips or bars. In each 40 channel 13, above the brake levers therein, is a plate or frame 43 having the guide legs 44 extending rearwardly therefrom, the frame fitting in the guide channel for movement therein. A boss 45 extends forwardly from 45 each plate or frame 43 through the slot 16 of the respective guide channel and serves to support a pivot pin 46 which pivotally receives the upper end of the corresponding operating arm 42. Each sash has an operating arm 42 extending upwardly from opposite sides thereof and pivoted to the frame 43 in the respective guide channel 13.

Each plate 43 has at its lower end a wedge projection 47 above the wedge levers 24 and 25 55 so that upon downward movement of the plate 43 the wedge projection will engage between and against the outer ends of the levers to spread them apart to force their brake lugs 27 into frictional engagement with the side 60 walls of the respective guide channel 13 to thus lock the window sash supporting bars 18 against vertical movement in the guide channels and thereby hold the upper pivot plates 43 in fixed position.

65 When the window sashes are in vertical or

closed position the operating arms will be parallel with the guide channels 13 and the wedge frame 43 will be above and disengaged from the brake levers 24 and 25. If it is desired to tilt the sash, as for example the 70 lower sash shown on the drawings, the sash is preferably first raised a short distance to carry its lower end above the sill 10 and then when the sash is swung outwardly on the pivot or trunnion pins 35 the operating arms 75 at the sides of the sash will be swung outwardly around the pivot pins 46 and the frames 43 will be shifted downwardly in the guide channels 13 to bring their wedge projections 47 into engagement with the brake levers to force the levers against the sides of the guide channels to thus lock the sash supporting bars 18 against vertical movement in the guide channels and to hold the frames 43 80 and pivot pins 46 against further downward movement in the channels. The sash will now be held by the supporting arms 42 in the slightly inclined or ventilating position. If it is desired to move the sash into horizontal or washing position its upper end is 85 swung outwardly, such outward swing causing the sash to fulcrum on the pivot pins 41 at the lower ends of the operating arms 42 so that the lower end of the sash will swing upwardly, being guided in such movement by 90 the guide frames 36 traveling through the guide channels and along the guide bars 18. When the sash has thus been swung down to horizontal or washing position, further 95 downward swing thereof will be prevented 100 by the abutment of the guide frames 36 against the abutments 48 secured to the guide bars 18. These abutments or stops 48 may be formed from sheet metal and bent to U shape 105 to fit the interior of the guide channels whereby to assist in keeping the bars 18 properly aligned within the guide channels.

When a sash has been tilted for ventilation or moved to horizontal position for washing it will be locked against vertical movement by 110 the brake levers. When the sash is swung upwardly from the horizontal position its inner end will descend, the guide frames 36 shifting downwardly back to their normal 115 positions at the lower ends of the guide channels and as the sash approaches vertical or closed position the wedge projection 47 will be disengaged from the brake levers so that when the sash assumes its vertical or closed position within the window frame it will be 120 again freed for ordinary vertical movement in the window frame for opening or closure in the ordinary manner.

The sash tape, the bars 18 and the various 125 guide frames therefor, and the wedge and brake elements are all within the guide channels 13 and well concealed and protected behind the channel flanges 14 and 15. The pivot fittings 33 and 38, and the operating arms 42 are received within the sides of the 130

sash frames outside of the inset walls 32, the outside walls of the sash being cut away sufficiently to leave clearance spaces 49 for outward passage of the operating arms.

6 The structure, from the inside, thus presents the appearance of an ordinary window.

During swing of a sash to inclined or horizontal position, and swing back of the sash to closed position, the friction of the guide frames 36 against the guide channels 13 and the bars 18, will more or less balance the weight of the sash so that it can be readily manipulated and will substantially self-lock itself in any position of inclination to which it has been moved and it will move easily and without jarring back into normal position.

I also provide improved lock mechanism for locking the sashes against swinging movement from their closed position. At 20 its upper end the brake frame 43 has the longitudinal notch 50 for receiving the outer end of a latch bolt 51 pivoted at its inner end to a fitting 52 secured to the inset wall 32 of the sash as by means of screws, the fitting having the concave upper end 52' for receiving the semi-circular end of the lock bolt, a spring 53 being secured to the bolt and abutting the end 52' of the fitting and tending to hold the lock bolt in outer horizontal position in the locking slot 50, the bolt extending through the slot 16 of the respective guide channel 13. Preferably there is a lock structure at each side of the sash and to unlock the sash I provide pins 54 each 35 having the head or knob 55 on its outer side, each pin extending through a vertical slot 56 in the front wall of the sash frame, a plate 57 being secured to the pin inside of the sash wall to hold the pin in the slot but to permit vertical shift thereof by means of the knob 55. Each lock bolt has a lateral abutment 58 above and in the path of the pin so that when the knob is pushed upwardly the pin will engage the abutment lug and swing the lock bolt upwardly out of the lock notch 50 to release the sash for swing in the window frame. The pressure of the spring 53 will press the abutment lug against the pin to press the pin against the side of the slot 56 so that the frictional engagement will lock the pin and knob in its upper or unlocking position. Before a sash can be 50 swung to inclined position the lock pins must be raised to withdraw the lock bolts, and then after the sash has been returned to normal position the pins may be shifted downwardly to release the lock bolts for relocking engagement in the lock slots 50.

60 I have described a practical and efficient embodiment of the features of my invention but I do not desire to be limited to the exact details of construction, arrangement, and operation as changes and modifications may be 65 made without departing from the scope of the

invention as defined in the appended claims. I claim as follows:

1. In window structure, the combination of a window frame, a window sash, guide channels at the opposite sides of said frame, a bar in each guide channel and a sash weight cable extending therefrom, slide frames in said channels guided therein by said bars and having pivotal connection with said sash at the lower corners thereof, operating arms extending from said sash, brake mechanism carried by each bar and brake operating mechanism in each channel connected with the upper end of the corresponding operating arm, swing of said sash causing cooperation of said brake actuating mechanisms with said brake mechanisms to lock said bars against vertical movement in said channels whereby said arms will be locked against vertical movement and will form a support for swing of said sash to horizontal position, said slide frames shifting upwardly with said sash during swing thereof to horizontal position, and stops on said bars for limiting the upward movement of said slide frames.

2. In window structure, the combination of a window frame having guide channels in its sides, a sash, a supporting structure for the sash in each guide channel, slidable members in said channels having pivotal connection with said sash at the lower corners thereof and receiving said supporting structures, operating arms extending from the sides of said sash, brake means on each supporting structure, a brake operating means in each channel above the respective brake means and having pivotal connection with the upper ends of said operating arms whereby swing of said sash will cause downward shift of the brake operating means into cooperation with the braking means, means whereby said cooperation will cause braking engagement of the braking means with the sides of the channels to thereby lock the supporting structures against vertical movement in said channels, further swing of said sash after operation of the brake mechanism causing said slide members to shift upwardly in said channels, and stops on said supporting structures for limiting the upward travel of said slide members.

3. In window structure, the combination of a window frame having side channels, a sash, sash supporting structure in each channel comprising slide frames having pivotal supporting connection with the sash at the lower end thereof, means for counterbalancing the weight of said supporting structures and sash, brake members carried by said supporting structures, actuating means in each channel above the brake members therein, operating arms extending between said sash and said actuating means for causing cooperation of said actuating means with said brake meim- 130

bers when said sash is moved to inclined position, means whereby such cooperation will cause brake engagement of the brake members with the channel sides to lock said supporting structures against vertical movement and to hold the upper ends of said arms against vertical movement, said arms when locked forming a support for swing of the sash into washing position and said slide members shifting upwardly in the channels with the lower end of the sash during such swing of the sash to washing position.

4. In window structure, the combination of a window frame having side channels, a sash, supporting structures in said channels, means connecting said sash for pivotal connection with and sliding connection relative to said supporting structures, arms pivoted at their lower ends to said sash, braking means within said channels between the upper ends of said arms and said supporting structures, and means whereby swing of said sash will cause operation of said braking mechanism to secure said supporting structures and the upper ends of said arms against movement relative to said channels.

5. In window structure, the combination of a window frame having side channels, a sash, supporting structure for the sash in each of said channels, means affording pivotal and slide connection between said sash and supporting structures, brake elements in each channel supported by the supporting structure therein, a wedge member in each channel above the brake elements, supporting side arms pivoted at their lower ends to said sash and pivoted at their upper ends to said wedge elements whereby tilting of said sash to inclined position will engage said wedge elements with said brake elements to spread said brake elements apart into braking engagement with the sides of said channels to thereby lock said supporting structures against vertical movement in said channels.

45 6. In window structure of the class described, the combination of a window frame having side channels, a sash, supporting means in each guide channel vertically shiftable therein, means pivotally connecting said sash at the lower end thereof with the supporting structures, counterbalance means connected with said supporting structures for counterbalancing the weight thereof and of said sash, brake levers pivoted on said supporting structures within said channels, wedge members shiftable in said channels above said brake levers, supporting arms extending from the sides of said sash and connecting at their upper ends with said wedge members whereby swing of said sash on its pivot support will cause said arms to shift said wedge members to spread apart the braking levers into braking engagement with the sides of said channels to thereby lock said

supporting structures against vertical movement in said channels.

7. In window structure of the class described, the combination of a frame having side grooves, stationary guide channels in said side grooves, a sash, a supporting bar in each channel for said sash having pivot connection at its lower end with the sash whereby said sash will move with said bars, counterbalance means connected with the upper ends of said bars for counterbalancing the weight thereof and of said sash, supporting side arms for said sash, brake structure on each bar, brake actuating means in each channel above the brake structure therein, the upper ends of said supporting arms being connected with said actuating means, swing of said sash on its pivot support and corresponding swing of said arms causing downward shift of said actuating means to operate said brake structure to lock said bars to said channels against vertical movement in said channels.

8. In window construction of the class described, the combination of side channels, a sash, supporting structure vertically shiftable in said channels, means affording pivotal connection between the lower end of the sash and the supporting structure whereby the sash may be swung to an angle with said channels, side arms extending upwardly from said sash, and braking structure in said channels operable by said arms when said sash is swung to inclined position to lock said bars against vertical movement in said channels.

9. In window frame structure of the class described, the combination of guide channels, a sash, supporting means in said channels for said sash comprising a pivotal connection, a lock bolt pivoted on said sash and normally extending into one of said channels, a lock abutment in said channel for normally receiving the bolt end to lock said sash against swinging movement on its pivot support, and a shiftable member on said sash for cooperating with said bolt to release it from said channel.

10. In window structure of the class described, the combination of a frame having side channels, a sash pivoted at its lower end for swinging movement to an angle with said channels, supporting arms extending upwardly from the sides of said sash, members slidably within said channels and having connection with the upper ends of said arms, locking notches in said sliding members, lock bolts on said sash normally extending into said locking notches to prevent swinging movement of the sash, and shiftable release members on said sash for moving said locking bolts to unlocking position to permit swing of said sash.

11. In window construction of the class described, the combination of side channels, a sash, supporting structure vertically shift-

- able in said channels, means affording pivotal connection between the lower end of the sash and the supporting structure whereby the sash may be swung to an angle with said channels,
 5 side arms extending upwardly from said sash, said side arms being free for bodily downward movement during initial swinging movement of said sash, and means operative after such initial swinging movement
 10 for interlocking the upper ends of said arms and side channels to prevent further bodily movement of said arms.
 12. In window construction of the class described, the combination of vertical side channels, a sash, means pivoting said sash at its lower end for swinging thereof relative to said channels, side arms pivoted at their lower ends to said sash, guide members in said channels above the upper ends of said arms,
 15 said guide members being free for movement in said channels during initial swing of said sash, and means operative after such initial swing for interlocking said guide members with said channels.
 20 13. In window construction of the class described, the combination of guide channels, a sash, lower guide members in said channels, means pivoting said sash at its lower end to said lower guide members, upper guide members in said channel, side arms pivoted at their lower ends to said sash and at their upper ends to said upper guide members, said upper guide members having limited downward movement in said channels and means
 25
 30
 35

for locking said members against further downward movement after such initial movement whereby said sash may be swung to ventilating position and held in such position, said arms then forming a support for further swing of said sash on its pivotal connection with said arms, said lower guide members guiding said sash during such additional swinging movement thereof.

14. In window structure of the class described, the combination of a window frame having guide channels in its sides, a sash, lower guide members in said guide channels and means pivoting said sash at its lower corners to said guide members, upper guide members in said channels, side arms pivoted at their upper ends to said upper guide members and pivoted at their lower ends to said sash intermediate the ends thereof, said upper guide members being adapted for limited downward movement in said channels whereby said sash may be swung on its lower pivot connection to a ventilating position, means for locking said upper guide members against further downward movement, said sash after locking of said upper guide members being turnable on its pivot connection with said side arms, said lower guide members moving upwardly in said guide channels to guide the turning movement of said sash, and means for limiting the upward movement of said lower guide members.
